TRUNNION TILT CORRECTOR

William H. Newell, Mount Vernon, and Lawrence S. Brown, Massapequa, N.Y., assignors to Sperry Rand Corporation, a corporation of Delaware

Application July 27, 1953, Serial No. 370,256

2 Claims. (Cl. 235—61.5)

The present invention relates to the art of determining certain correctional factors required for accurate aiming in the fire of ordnance and more particularly to a method and apparatus for determining trunnion tilt correction.

The invention is particularly useful in connection with a fire control system, in which a gun or like ordnance to be controlled is supported on a movable platform such as a ship's deck. Since the ship will roll and pitch, angles measured in the deck plane usually vary in phase with the ship's angular movement and hence must be corrected to determine certain fire control quantities. The so-called "computer" in a fire control system provides a continuous solution for the train and elevation of a particular target and must operate relative to the horizontal plane. However, the line of sight (involving either optical or radar tracking) is determined by the director of the fire control system, relative to the deck plane. The conversion of director information to define the line of sight relative to the horizontal plane is accomplished by the deck tilt corrector. It is necessary for accurate firing, to convert the line of bore (gun axis) coordinates in the horizontal plane as determined by the computer back into coordinates relative to the deck plane, by means of a trunnion tilt corrector.

The mechanization of trunnion tilt correctional equations which are not true solution equations introduces errors affecting adversely the accuracy of determination of trunnion tilt correction quantities.

One object of the present invention is to provide a new and improved method and instrument, by which the necessary values of trunnion tilt correction, are accurately and continuously computed, thus eliminating the effect of angular movement of the deck and causing thereby the system to operate accurately as if said system were supported upon a stable platform.

As a feature of the present invention, there are derived true solution formulas for certain trunnion tilt correctional angles in terms of available quantities. From the main computing section of the fire control system, there is available (1) the elevation angle between the line of gun bore and its projection on the horizontal plane and (2) the horizontal sight projections of the line of bore and the line of sight and from the stable element on the ship, there is available (3) the level angle between the horizontal and deck planes measured in the vertical plane through the line of sight and (4) the cross-level angle between the vertical plane through the line of sight and a plane perpendicular to the deck plane through the projection of the line of sight on the deck plane. From these four available quantities, true solution formulas are derived in accordance with the present invention for (1) the deck sight deflection angle between the vertical plane through the line of sight and the plane perpendicular to the deck plane through the line of bore, as measured in the deck plane and (2) the elevation correction angle defined by

$$V_z = E'g - (Eg + L)$$

where $E'g$ is the angle between the line of bore and its projection on the deck plane, Eg is the elevation angle available as indicated above and L is the level angle available as indicated above.

2

The true solution formulas are mechanized with the four available quantities described above as inputs, to give continuous solutions for the deck sight deflection angle and the elevation correction angle defined above. Each of the formulas is solved continuously for a corresponding trunnion tilt correction by a servo or null seeking system, which so drives the trunnion tilt correction line, that a balance is obtained between the quantities on opposite sides of the equality sign of the formula.

Various other objects, features and advantages of the present invention are apparent from the following particular description and from an inspection of the accompanying drawings, in which

Fig. 1 is a simplified block diagram showing the functional relationship between different components of a suitable gun fire control system, into which the trunnion tilt corrector of the present invention may be incorporated;

Fig. 2 is a simplified block diagram showing a gun order device or network which forms part of the fire control system of Fig. 1 and which includes the trunnion tilt corrector of the present invention;

Fig. 3 is a spherical diagram of the trunnion tilt problem solved in accordance with the present invention; and

Fig. 4 is a simplified block diagram of the trunnion tilt corrector embodying the present invention.

A tabulation of symbols and terms used in the derivation of formulas herein, in the drawings and in the description is submitted herein:

(B'gr) Gun Train Order Angle—the ordered angle between the vertical plane through the ship's centerline and the vertical plane through the gun bore axis, measured in the deck plane clockwise from the bow.

(B'r) Director Train Angle—the angle between the vertical plane through the ship's centerline and the vertical plane through the line of sight, measured in the deck plane clockwise from the bow.

(bh.Ph) Train Parallax Correction for gun director's horizontal base.

(bh.Pv) Elevation Parallax Correction for gun director's horizontal base.

(Dd) Deck Sight Deflection Angle—The angle between the vertical plane through the line of sight and the plane perpendicular to the deck plane through the line of bore of the gun (gun axis), as measured in the deck plane.

(Dh) Horizontal Sight Deflection Angle—the angle between the vertical plane through the line of sight and the vertical plane through the line of bore, measured in the horizontal plane, clockwise from the vertical plane through the line of sight.

(Eg) Vertical Gun Elevation Angle—the angle between the line of bore and its projection on the horizontal plane.

(E'g) Gun Elevation Order Angle—the ordered angle between the line of bore and its projection on the deck plane.

(L) Level Angle—the angle between the deck plane and the horizontal plane measured in the vertical plane through the line of sight, this angle being positive when the portion of the deck towards the target is down.

(Vz) Correction Angle to Gun Elevation—compensating for trunnion tilt and defined by $V_z = E'g - (Eg + L)$.

(Zd) Cross-Level Angle—the angle between the vertical plane through the line of sight and the plane perpendicular to the deck plane through the intersection of the deck plane and the vertical plane through the line of sight.

A suitable fire control system capable of solving gun fire control problems both anti-aircraft and surface is illustrated in simplified form in Fig. 1. This fire control

system may comprise a computer assembly 10, a gun director 11, and a stable element 12. The computer assembly 10 includes a prediction network for determining horizontal sight deflection Dh and vertical gun elevation Eg , a parallax correction network for determining train parallax correction ($bh.Ph$) and elevation parallax correction ($bh.Pv$), and a gun order device or network shown in simplified form in Fig. 2. This gun order device or network may comprise a trunnion tilt corrector 14, which is the subject of the present invention and which operates in conjunction with a number of adding components or differentials 16, 17, 18 and 19 to make up the gun orders from (1) the Dh and Eg outputs from the prediction network, (2) the ($bh.Ph$) and ($bh.Pv$) outputs from the parallax correction network, (3) the L and Zd outputs from the stable element 12 (Fig. 1), and (4) the $B'r$ output from the gun director 11 (Fig. 1). The trunnion tilt corrector 14 in this gun order network has inputs Dh , Eg , L and Zd and outputs ($L+Vz$) and Dd .

The gun elevation order $E'g$ and gun train order $B'gr$ are computed by the gun order device or network of Fig. 2 according to the following equations:

$$E'g = Eg + L + Vz + (bh.Pv)$$

$$B'gr = B'r + Dd + (bh.Ph)$$

Gun elevation order $E'g$ is sent to the gun mounts while gun train order $B'gr$ is sent to the gun mounts and the parallax correction network.

In accordance with the present invention, true solutions for the trunnion tilt problems are employed, thereby eliminating errors, such as those which would be inherent, if empirical solutions were employed. As a result of the procedure of the present invention, true solution formulas are obtained for trunnion tilt corrections Dd (deck deflection) and Vz (elevation correction) in terms of the available quantities Eg (elevation order), Dh (deflection order), L (level) and Zd (cross-level). These formulas are solved for trunnion tilt corrections Eg and Vz by servo or null seeking systems which so position the Dd and Vz lines, that a balance is obtained between the quantities represented by the right and left hand terms of each equation.

The trunnion tilt correction problems are indicated in the spherical diagram shown in Fig. 3. These problems are solved in accordance with true solutions, using as inputs the vertical gun elevation Eg and the horizontal sight deflection Dh obtained from the prediction network of the computer 10 (Fig. 1) and the level L and cross-level Zd obtained from the stable element 12 (Fig. 1).

Dd solution

From the spherical trigonometry of Fig. 3, the following relationship can be ascertained

$$\sin Dd = \sin T \sin (M+U+L)$$

Expanding $\sin [M+(U+L)]$

$$\sin Dd = \sin T [\sin M \cos (U+L) + \cos M \sin (U+L)]$$

$$(1) \quad \sin Dd = \sin T \sin M \cos (U+L) + \sin T \cos M \sin (U+L)$$

$$\sin M = \tan P \cot T = \tan P \frac{\cos T}{\sin T}$$

$$(2) \quad \sin M \sin T = \tan P \cos T$$

$$(3) \quad \cos T = \cos Dd \sin (90-Zd) = \cos Dd \cos Zd$$

Substituting 3 in 2:

$$(4) \quad \sin M \sin T = \tan P \cos Dd \cos Zd$$

Expressing $\cos M$ as $\cos [(M+U+L)-(U+L)]$

$$(5) \quad \cos M = \cos (M+U+L) \cos (U+L) + \sin (M+U+L) \sin (U+L)$$

Substituting 4 and 5 in 1

$$5 \quad \sin Dd = \tan P \cos Dd \cos Zd \cos (U+L)$$

$$+ \sin T \sin (U+L) [\cos (M+U+L)$$

$$\cos (U+L) + \sin (M+U+L) \sin (U+L)]$$

$$10 \quad (6) \quad \sin Dd = \cos Dd \tan P \cos Zd \cos (U+L)$$

$$+ \sin T \sin (U+L) \cos (U+L) \cos$$

$$(M+U+L) + \sin T \sin (M+U+L) \sin^2 (U+L)$$

$$\cos (M+U+L) = \cot T \cot (90-Zd)$$

$$= \frac{\cos T \cos (90-Zd)}{\sin T \sin (90-Zd)}$$

$$15 \quad (7) \quad = \frac{\cos T \sin Zd}{\sin T \cos Zd}$$

Substituting 3 in 7

$$20 \quad \cos (M+U+L) = \frac{\cos Dd \cos Zd \sin Zd}{\sin T \cos Zd}$$

$$(8) \quad \cos (M+U+L) = \frac{\cos Dd \sin Zd}{\sin T}$$

$$(9) \quad \sin Dd = \sin (M+U+L) \sin T$$

$$25 \quad \sin (M+U+L) = \frac{\sin Dd}{\sin T}$$

Substituting 8 and 9 in 6

$$30 \quad \sin Dd = \cos Dd \tan P \cos Zd \cos (U+L) + \cos Dd$$

$$\sin Zd \sin (U+L) \cos (U+L) + \sin Dd \sin^2 (U+L)$$

$$\sin Dd [1 - \sin^2 (U+L)] = \cos Dd \tan P \cos Zd \cos$$

$$(U+L) + \sin Zd \sin (U+L) \cos (U+L)]$$

$$35 \quad \tan Dd = \frac{\tan P \cos Zd + \sin Zd \sin (U+L)}{\cos (U+L)}$$

$$(10) \quad \tan Dd = \tan P \cos Zd \sec (U+L)$$

$$+ \sin Zd \tan (U+L)$$

$$40 \quad \tan P \cos Zd \sec (U+L) = \frac{\tan P \cos Zd}{\cos (U+L)}$$

$$= \frac{\cos Zd \tan P}{\cos U \cos L - \sin U \sin L}$$

$$45 \quad (11) \quad = \frac{\cos Zd \tan P}{\cos U \cos L}$$

$$= \frac{1 - \tan U \tan L}{1 - \tan U \tan L}$$

By constructing great circle arc C in Fig. 3:

$$50 \quad \cos C = \cos P \cos U$$

$$\cos C = \cos Eg \cos Dh$$

$$(12) \quad \cos P \cos U = \cos Eg \cos Dh$$

In triangle comprised by P and the zenith

$$55 \quad \sin P = \sin (90-Eg) \sin Dh = \cos Eg \sin Dh$$

$$(13) \quad \cos Eg = \frac{\sin P}{\sin Dh}$$

Substituting 13 in 12

$$60 \quad \cos P \cos U = \frac{\sin P \cos Dh}{\sin Dh}$$

$$(14) \quad \tan P = \frac{\cos U \sin Dh}{\cos Dh} = \cos U \tan Dh$$

65 Substituting 14 in 11:

$$(15) \quad \tan P \cos Zd \sec (U+L) = \frac{\cos Zd \tan Dh \sec L}{1 - \tan U \tan L}$$

Substituting 15 in 10 and expanding $\tan (U+L)$

$$(16) \quad \tan Dd = \frac{\cos Zd \tan Dd \sec L}{1 - \tan U \tan L} + \frac{\sin Zd \tan U + \sin Zd \tan L}{1 - \tan U \tan L}$$

$$\frac{\cos Zd \tan Dh \sec L + \sin Zd \tan U + \sin Zd \tan L}{1 - \tan U \tan L}$$

In the spherical triangle comprised by (90-Eg), (90-U), and P:

$$\cos(90-U) \cos P = \cos(90-Eg)$$

$$(17) \quad \sin U = \frac{\sin Eg}{\cos P}$$

From 12

$$(18) \quad \cos U = \frac{\cos Eg \cos Dh}{\cos P}$$

From 17 and 18

$$(19) \quad \tan U = \frac{\sin Eg}{\cos Eg \cos Dh} = \frac{\tan Eg}{\cos Dh}$$

Substituting 19 in 16

$$\begin{aligned} \tan Dd &= \frac{\cos Zd \tan Dh \sec L + \sin Zd \frac{\tan Eg}{\cos Dh} + \sin Zd \tan L}{1 - \frac{\tan Eg}{\cos Dh} \tan L} \\ &= \frac{\cos Zd \tan Dh \sec L \cos Eg \cos Dh + \sin Zd \sin Eg + \sin Zd \tan L \cos Eg \cos Dh}{\cos Eg \cos Dh - \sin Eg \tan L} \\ &= \frac{\cos Zd \sin Dh \cos Eg \cos Dh}{\cos Dh \cos L} + \frac{\sin Zd \sin Eg + \sin Zd \sin L \cos Eg \cos Dh}{\cos L} \\ &= \frac{\cos Eg \cos Dh - \sin Eg \frac{\sin L}{\cos L}}{\cos Eg \cos Dh - \sin Eg \frac{\sin L}{\cos L}} \end{aligned}$$

$$\sin Dd = \frac{\cos Zd \sin Dh \cos Eg + \sin Zd \sin Eg \cos L + \sin Zd \sin L \cos Eg \cos Dh}{\cos Eg \cos Dh \cos L - \sin Eg \sin L}$$

$$(20) \quad \begin{aligned} &\sin Dd [\cos Eg \cos Dh \cos L - \sin Eg \sin L] \\ &= \cos Dd (\cos Zd \sin Dh \cos Eg + \sin Zd \sin \\ &\quad Eg \cos L + \sin Zd \sin L \cos Eg \cos Dh) \end{aligned}$$

Equation 20 constitutes the solution equation for the Dd servo in the mechanization of the equation. Voltages in accordance with the left hand side are applied in opposite sign to those of the right hand side to the servo error detector. The servo then positions itself such, that the equation is balanced and its dial reads the computed value of Dd for the particular values of the input quantities at the moment.

Vz solution

From the spherical trigonometry of Fig. 3, the following relationships can be ascertained:

Defining Vz as follows:

$$Vz = E'g - Eg - L = E'g - (Eg + L)$$

$$\sin Vz = \sin [E'g - (Eg + L)]$$

$$(21) \quad \sin Vz = \sin E'g \cos (Eg + L) - \cos E'g \sin (Eg + L) \sin E'g = \sin (Eg + L) \cos Zd$$

$$(22) \quad \sin E'g = \sin Eg \cos L_1 \cos Z_1 + \cos Eg \sin L_1 \cos Z_1 \cos N = \cos L_1 \cos Z_1 \cos N = \cos L \cos Zd$$

$$(23) \quad \cos L_1 \cos Z_1 = \cos L \cos Zd$$

$$(24) \quad \sin L_1 \cos Z_1 = \cos L \cos Zd \tan L_1$$

$$(25) \quad \tan L_1 = \sin V \tan N \tan L = \sin (V + Dh) \tan T$$

$$(26) \quad \tan N = \frac{\tan L}{\sin (V + Dh)}$$

Expressing V as $(V + Dh) - Dh$

$$(27) \quad \sin V = \sin (V + Dh) \cos Dh - \cos (V + Dh) \sin Dh$$

Substituting 26 and 27 in 25

$$\tan L_1 = \frac{\sin (V + Dh) \cos Dh \tan L}{\sin (V + Dh)} - \cos (V + Dh) \sin Dh \tan N$$

$$(28) \quad \tan L_1 = \cos Dh \tan L - \frac{\cos (V + Dh) \sin Dh \sin N}{\cos N}$$

$$(29) \quad \cos (V + Dh) \sin N = \sin Zd$$

Substituting 29 in 28

$$(30) \quad \tan L_1 = \cos Dh \tan L - \frac{\sin Zd \sin Dh}{\cos N}$$

$$(31) \quad \cos N = \cos L \cos Zd$$

Substituting 31 in 30

$$(32) \quad \tan L_1 = \tan L \cos Dh - \tan Zd \sin Dh \sec L$$

Substituting 23, 24 and 32 in 22

$$\begin{aligned} \sin E'g &= \sin Eg \cos L \cos Zd + \cos Eg \cos L \\ &\quad \cos Zd \tan L \cos Dh - \cos Eg \cos L \\ &\quad \cos Zd \tan Zd \sin Dh \sec L \end{aligned}$$

$$(33) \quad \sin E'g = \frac{\sin Eg \cos L \cos Zd + \cos Eg \sin L}{\cos Zd \cos Dh - \cos Eg \sin Zd \sin Dh}$$

From the spherical diagram of Fig. 3, the following relationship can be ascertained:

$$(34) \quad \cos E'g \cos Dd = \cos P \cos (U + L) = \cos P \cos U \cos L - \cos P \sin U \sin L$$

Substituting 12 and 17 in 34

$$(35) \quad \cos E'g \cos Dd = \cos Eg \cos Dh \cos L - \sin Eg \sin L$$

Rearranging Equation 33

$$(36) \quad \sin Eg \cos L \cos Zd + \cos Eg \sin L \cos Zd \cos Dh - \cos Eg \sin Zd \sin Dh = \sin E'g$$

Multiplying corresponding sides of 35 and 36

$$(37) \quad Q \cos E'g \cos Dd = (\cos Eg \cos Dh \cos L - \sin Eg \sin L) \sin E'g$$

Where

$$Q = (\sin Eg \cos L \cos Zd + \cos Eg \sin L \cos Zd \cos Dh - \cos Eg \sin Zd \sin Dh)$$

55 This Equation 37 constitutes the solution equation for the Vz servo. Although Vz does not appear explicitly in the equation, its solution is effected by including it through a differential resolver in the quantity

$$E'g = Eg + L + Vz$$

The solution Equation 20 for obtaining the quantity Dd (deck sight deflection), must be rearranged and equated to zero, to determine the polarity of each of the two main computation channels for mechanization.

$$0 = \cos Dd (\cos Zd \sin Dh \cos Eg + \sin Zd \sin Eg \cos L + \sin Zd \sin L \cos Eg \cos Dh) - \sin Dd (\cos Eg \cos Dh \cos L - \sin Eg \sin L)$$

70 Therefore, the Equation 20 to be mechanized for the quantity Dd involves the following two main channels:

$$(1) \quad \cos Dd (\cos Zd \sin Dh \cos Eg + \sin Zd \sin Eg \cos L + \sin Zd \sin L \cos Eg \cos Dh)$$

$$(2) \quad -\sin Dd (\cos Eg \cos Dh \cos L - \sin Eg \sin L)$$

In a similar manner, the solution Equation 37 for obtaining the quantity V_z (elevation correction) must be rearranged and equated to zero, to determine the polarity of each of the two main computation channels for mechanization:

$$0 = Q \cos E'g \cos Dd - (\cos Eg \cos Dh \cos L - \sin Eg \sin L) \sin E'g$$

Where

$$Q = (\sin Eg \cos L \cos Zd + \cos Eg \sin L \cos Zd \cos Dh - \cos Eg \sin Zd \sin Dh)$$

Therefore, the Equation 37 to be mechanized for the quantity V_z involves the following two main channels

$$(3) Q \cos E'g \cos Dd$$

$$(4) -(\cos Eg \cos Dh \cos L - \sin Eg \sin L) \sin E'g$$

The computer for solving the Equation 20 is essentially one in which quantities in the form of the proper functions of input and output quantities are added, subtracted and multiplied in each of the channels of computation 1 and 2. From Equation 20, it is seen that the summation of these two channels 1 and 2 should be zero. Consequently, the output of a two input differential or adding device, is used as a servo input to drive a line in accordance with the quantity Dd . When the servo nulls the output of this adding device, the equation of this solution has been satisfied.

Similarly, the two channels of Computation 3 and 4 are fed as inputs into an adding device to obtain an output which is used as a servo input and which when nulled, satisfies the Equation 37, thereby producing a line drive according to the quantity V_z .

The trunnion tilt corrector employed for the mechanization of Equations 20 and 37 is made up of a series of components, which may be of any suitable design, and which per se, form no part of the present invention. Fig. 4 therefore, shows this trunnion tilt corrector diagrammatically in block form. The specific corrector shown as an example, is essentially an electrical one, the solid lines indicating electrical connections and the dotted lines indicating mechanical lines or movements arising, for example, from shaft rotations.

The specific trunnion tilt corrector shown in Fig. 4 utilizes 400 cycle per sec. A.C. as a computing reference, with an input level of 12 volts, the representation of data by the 400-cycle voltage being such, that the root mean square value of each voltage is proportional to the quantity represented. For the purpose of discussion, this reference voltage is regarded as (+1). The different computed quantities are indicated in Fig. 4 without parametric coefficients. These coefficients are a function of the reference voltage (12 volts) and the characteristics of the constituent elements of the networks or loops involved and are constant for any one mechanism.

Channel 1

$$\cos Dd (\cos Zd \sin Dh \cos Eg + \sin Zd \sin Eg \cos L + \sin Zd \sin L \cos Eg \cos Dh)$$

The main components employed in the mechanization of Equations 20 and 37 aside from the servo mechanisms are angle function computers or resolvers. These resolvers may be of any suitable type, as for example, of the magnetic type disclosed in application Serial No. 157,892 filed April 25, 1950, now Patent No. 2,646,218. The function of these resolvers is to produce an output voltage proportional to a sine or cosine function of an angle which is introduced mechanically. The circuit of such a resolver resembles a synchro control transformer in construction, except for the number and distribution of windings and comprises essentially of a stator having two separate distributed windings arranged in space quadrature and constituting primary windings and a rotor having two separate distributed windings in space quadrature constituting secondary windings.

In operation, the specific magnetic resolver described

acts as a single-phase transformer with a variable coupling between primary and secondary. As the rotor turns, the voltage across each secondary winding changes. Construction of the resolver is such that the secondary voltages vary as the sine or cosine of the angle through which the rotor turns. In some resolvers, both rotor and stator can turn.

In operation, the angle as a mechanical quantity turns the rotor. A voltage energizes the stator. Assuming the stator to be fixed, voltages corresponding to the product of the stator energizing voltage and sine and cosine of the angle are computed at the rotor windings. If instead of being fixed, the stator is turned through an angle in the opposite direction to the rotor, the outputs are proportional to the sine and cosine of the sum of the stator and rotor angles. If the stator is turned through an angle in the same direction as the rotor, the outputs are proportional to the sine and cosine of the difference between the two angles.

Where two voltages are imposed upon the resolver in conjunction with the mechanical input whose trigonometric function is to be computed, these two voltages are algebraically added in the resolver in any suitable manner before being impressed upon the stator.

In some cases, the resolver may include a differential to add quantities for resolution into the trigonometric functions.

Since it is impracticable to design a computing resolver that has no output voltage wave-shape distortion and therefore no appreciable error, the basic resolver circuit described gives only approximate results. Reduction of the error to a negligible amount is accomplished by an error compensating loop described in the aforesaid application Serial No. 157,892, now Patent No. 2,646,218.

This error compensating loop attenuates the distortion by introducing a high gain amplifier ahead of the computing resolver and connecting an error compensating resolver in parallel with the computing resolver and to the output of the amplifier. This error compensating resolver is identical electrically and magnetically with the computing resolver and the two resolvers may have a common primary (stator). The output of error compensating resolver is fed back as a negative feed-back to the input of the amplifier. The rotor of this error compensating resolver is set by adjustment and clamped to obtain correct output voltages from the computing resolver.

In the following description of the trunnion tilt corrector, it is assumed that the resolvers mentioned are of the magnetic type described, although they may be of any suitable type.

In the mechanization of computation channel 1, a reference voltage (12 volts) and the mechanical elevation quantity (Eg) as computed in the main computing section of the fire control system, are fed as inputs into a resolver 21. The $\sin Eg$ voltage output of this resolver 21 and the mechanical level quantity (L) obtained from the stable element of the ship are fed as inputs into a resolver 22, and the $\cos Eg$ voltage output of the resolver 21 and the mechanical horizontal sight deflection quantity Dh , as computed in the computer 10 (Fig. 1), of the fire control system, are fed as inputs into a resolver 23. The $\cos Eg \cos Dh$ voltage output of the resolver 23 and the mechanical level quantity (L) are brought into a resolver 24. The $\cos Eg \cos Dh \sin L$ voltage output of this resolver 24 and the $\sin Eg \cos L$ voltage output of this resolver 22, totally $(\sin Eg \cos L + \cos Eg \cos Dh \sin L)$ volts, are fed into a resolver 25 in conjunction with the mechanical cross-level quantity (Zd) obtained from the stable element of the ship. The voltage output $\cos Eg \sin Dh$ from the resolver 23 is delivered to a resolver 26 in conjunction with the mechanical cross-level quantity (Zd), and the voltage output $\cos Eg \sin Dh \cos Zd$ from this resolver 26 and the voltage output $(\sin Eg \cos L + \cos Eg \cos Dh \sin L) \sin Zd$ from the resolver 25, totally $(\sin Eg \cos L \sin Zd + \cos Eg \cos Dh \sin L \sin Zd + \cos$

$Eg \sin Dh \cos Zd$ volts, are fed into a resolver 27 into which is also delivered the mechanical deck sight deflection quantity Dd obtained from the output of the trunnion tilt corrector in the manner to be described. The voltage output of this resolver 27 is $\cos Dd (\sin Eg \cos L \sin Zd + \cos Eg \cos Dh \sin L \sin Zd + \cos Eg \sin Dh \cos Zd)$ which is the desired quantity of channel 1.

Channel 2

$$-\sin Dd (\cos Eg \cos Dh \cos L - \sin Eg \sin L)$$

In the mechanization for computation channel 2, the voltage output $-\sin Eg \sin L$ from the resolver 22 and the voltage output $\cos Eg \cos Dh \cos L$ from the resolver 24, totally $(\cos Eg \cos Dh \cos L - \sin Eg \sin L)$ volts, are fed as inputs into a resolver 28, having as a mechanical input the deck sight deflection quantity (Dd) obtained from the output of the trunnion tilt corrector to produce a $(-\sin Dd)$ operator in the resolver 28. The voltage output of this resolver 28 is $-(\cos Eg \cos Dh \cos L - \sin Eg \sin L) \sin Dd$ which is the desired quantity of channel 2.

Production of (Dd) from channels 1 and 2

The two voltage outputs of computation channels 1 and 2 are conducted to a suitable summing device 32, which may be an adding network, comprising two input resistors in parallel, a computing amplifier at the common connection of these resistors having a very large gain, so as to draw no significant current from this point and to maintain this connection at a zero potential, a feedback resistor and a load resistor. The different resistance ratios are selected to convert the two input voltages to a common scale, i.e., to the same value per volt.

Theoretically, according to Equation 20, the summation of the computation channels 1 and 2 should be zero. If the conditions of the Equation 20 are not satisfied, an error is produced at the output of the summing device 32, which in the case of an electrical system such as that of Fig. 4, is a voltage having the proper polarity to drive the servo motor of a servo mechanism 33 of the well-known type, to produce a null in the error voltage. When this null is achieved, the value of (Dd) converted into a mechanical quantity (shaft rotation) becomes one of the trunnion tilt correction quantities.

A servo mechanism, such as the servo mechanism 33, is an automatic drive which positions a mechanical load in accurate correspondence with an input, without placing an appreciable load upon this input. The input can be either mechanical or electrical (in Fig. 4, the input is electrical) but the output is always mechanical.

The basic components of the specific servo mechanism shown in Fig. 4 comprises a servo control 34, a servo amplifier 35, a servo motor 36, and an induction generator 37, connected in a double loop circuit with a control network which in the present case is the summing loop 32. Essentially, the control network 32 computes a voltage proportional to the error between a function of the input and a function of the output. This error voltage is converted to a frequency of 60 cycles by the servo control 34, amplified by the servo amplifier 35 and finally supplied to the servo motor 36 for its control. The servo motor 36 furnishes the mechanical output and drives the induction generator 37. From this generator 37, a voltage proportional to the output velocity is supplied to the servo control 34. After being modified by computing elements in the servo control 34, the modified voltage is combined with the error voltage to improve the operation of the servo mechanism.

The output mechanical quantity (Dd) from the servo mechanism 33, which is the quantity sought is fed back as a mechanical input into the resolvers 27 and 28, for the purpose already indicated.

Channel 3

$$Q \cos E'g \cos Dd$$

where

$$Q = (\sin Eg \cos L \cos Zd + \cos Eg \sin L \cos Zd \cos Dh - \cos Eg \sin Zd \sin Dh)$$

In the mechanization of computation channel 3, the voltage output $(\sin Eg \cos L + \cos Eg \cos Dh \sin L) \cos Zd$ from the resolver 25 and the voltage output $-\cos Eg \sin Dh \sin Zd$ from the resolver 26 are fed into a resolver 29, and the sum of these voltage outputs is multiplied by the operator $\cos Dd$ in the resolver 29 to produce the voltage output $Q \cos Dd$. This latter output from the resolver 29 is fed into a resolver 30, into which is also fed as inputs the mechanical elevation quantity Eg , as computed in the computer 10 (Fig. 2) of the fire control system, and the mechanical summation quantity ($L + Vz$) obtained by adding mechanically in any suitable manner, the level (L) derived from the stable element and the 15 elevation correction quantity Vz derived as one of the outputs of the trunnion tilt corrector, in a manner to be described. The operating factor $\cos (Eg + L + Vz)$ or $\cos E'g$ computed in the resolver 30 from these mechanical input quantities are multiplied therein by the input voltage $Q \cos Dd$ to obtain a voltage output from said resolver 30 corresponding to the quantity $Q \cos Dd \cos E'g$, which in in turn corresponds to the desired channel 3.

Channel 4

$$-(\cos Eg \cos Dh \cos L - \sin Eg \sin L) \sin E'g$$

In the mechanization of computation channel 4, the voltage output $\cos Eg \cos Dh \cos L$ from the resolver 24 and the voltage output $(-\sin Eg \sin L)$ from the resolver 22 are fed as inputs for addition into a resolver 31, into which is also fed as inputs the mechanical quantity Eg and the mechanical summation quantity ($L + Vz$), as in the case of the resolver 30. The operating factor $\sin (Eg + L + Vz)$ or $\sin E'g$ computed in the resolver 31 from these mechanical input quantities is multiplied therein by the sum of the voltage inputs into said resolver to produce the voltage output $-(\cos Eg \cos Dh \cos L - \sin Eg \sin L) \sin E'g$ corresponding to the desired channel 4.

Production of (Vz) from channels 3 and 4

The two voltage outputs of computation channels 3 and 4 are conducted to a suitable summing device 40, which may be an adding network similar to the adding network 32.

Theoretically, according to Equation 37, the summation of the computations 3 and 4 should be zero. If the conditions of the Equation 37 are not satisfied, an error is produced at the output of the summing device 40, which in the case of an electrical system such as that of Fig. 4, is a voltage having the proper polarity to drive the servo motor of a servo mechanism 41, similar to the servo mechanism 33, to produce a null in the error voltage. When this null is achieved, the value of (Vz) converted into a mechanical quantity (shaft rotation) becomes one of the trunnion tilt quantities required.

Equations 20 and 37 mechanized by the trunnion tilt corrector 14 of the present invention can be expressed in different forms, as for example, by the substitution of trigonometric equivalents, without altering the basic substance of the equations. It should be understood therefore, that the references to the specific equations in the following claims cover such equivalent substitutions.

In the following claims, by "mechanical operation," "mechanizing," and kindred terms it is intended to cover not only the use of strictly mechanical expedients but also electrical devices as well.

While the invention has been described with particular reference to a specific embodiment, it is to be understood that it is not to be limited thereto, but is to be construed broadly and restricted solely by the scope of the appended

claims as interpreted in accordance with the above explanation.

What is claimed is:

1. A device for continuously computing the deck sight deflection angle (Dd) for trunnion tilt correction in a gun fire control system, comprising means for continuously mechanizing for the quantity (Dd), the equation containing the two main group terms as follows:

$$0 = \cos Dd (\cos Zd \sin Dh \cos Eg + \sin Zd \sin Eg \cos L + \sin Zd \sin L \cos Eg \cos Dh) - \sin Dd (\cos Eg \cos Dh \cos L - \sin Eg \sin L),$$

wherein (Eg) represents the vertical gun elevation angle, (Dh) the horizontal sight deflection angle, (L) the level angle, (Zd) the cross-level angle and $E'g = Eg + L + V_z$, said mechanizing means including two computation channels with outputs corresponding to said main group terms respectively, means for adding said channel outputs, and a servomechanism for driving a (Dd) line having as input the output of said adding means.

2. A device for continuously computing the correction angle to gun elevation (Vz) for trunnion tilt correction in a gun fire control system, comprising means

for continuously mechanizing for the quantity (Vz), the equation containing the two main group terms as follows:

$$0 = Q \cos E'g \cos Dd - (\cos Eg \cos Dh \cos L - \sin Eg \sin L) \sin E'g,$$

wherein

$$Q = (\sin Eg \cos L \cos Zd + \cos Eg \sin L \cos Zd \cos Dh - \cos Eg \sin Zd \sin Dh),$$

10 (Eg) represents the vertical gun elevation angle, (Dh) the horizontal sight deflection angle, (L) the level angle, (Zd) the cross-level angle and $E'g = Eg + L + V_z$, said mechanizing means including two computation channels with outputs corresponding to said main group terms respectively, means for adding said channel outputs, and a servomechanism for driving a (Vz) line having as input the output of said adding means.
